UNITED STATES PATENT OFFICE.

ARTHUR DICKERSON, OF SALT LAKE CITY, UTAH, ASSIGNOR TO DICKERSON MANUFACTURING COMPANY, OF SALT LAKE CITY, UTAH, A CORPORATION.

IGNITION DEVICE.

1,254,584.

Specification of Letters Patent. Patented Jan. 22, 1918.

Application filed September 17, 1917. Serial No. 191,882.

To all whom it may concern:

Be it known that I, ARTHUR DICKERSON, a citizen of the United States, residing at Salt Lake City, in the county of Salt Lake and State of Utah, have invented certain new and useful Improvements in Ignition Devices, of which the following is a specification.

My invention relates to ignition devices for internal combustion engines and has for its object to provide an ignition device whereby a low tension electric circuit may be changed and the voltage increased and automatically distributed and timed to cause the ignition of the compressed gases in the respective cylinders with less wiring, fewer parts and economy of space, cost of construction and intricacy of adjustment now in use, and particularly to provide a compact device whereby one coil may be used with a source of current and the increased voltage distributed and timed to cause the ignition of the compressed gases in any number of the co-acting cylinders.

These objects I accomplish with the device illustrated in the accompanying drawings in which similar letters and numerals of reference indicate like parts throughout the several figures as described in the specification forming a part of this application and pointed out in the appended claims.

In the drawings in which I have shown a substantial embodiment of my invention Figure 1 is a diagrammatic view of a four cylinder internal combustion engine with my device in place thereon. Fig. 2 is a front elevation of the contact arm. Fig. 3 is a side elevation of the distributor case a portion shown in section and a portion in dotted lines. Fig. 4 is an end view showing the interior of said casing. Fig. 5 is an end elevation of the cap for said casing. Fig. 6 is a side elevation of said cap and lead wires, portions shown in section. Fig. 7 is an end elevation of the distributor disk. Fig. 8 is a side elevation of the distributor disk and operating shaft. Fig. 9 is a longitudinal section of the timer somewhat enlarged from the other figures. Fig. 10 is a detail in section of one of the timer nuts and low tension post. Fig. 11 is a detail in section of the contact thimble. Fig. 12 is a detail in section of the insulating tube. Fig. 13 is a detail in section of the threaded sleeve and

post holder. Fig. 14 is a detail in section of the contact plunger.

In the drawings illustrating my device a diagrammatic engine having four cylinders is shown as A and as will be obvious with but slight changes my device may be used on engines of more or less cylinders. The source of the electric energy is shown as a battery B and the single induction coil used is shown at C. The individual spark plugs are shown as 1, 2, 3, and 4 respectively and the timing shaft of the engine is shown at D. On the end of said shaft D is secured and operated therewith a sprocket wheel 5. My device is mounted on the upper side of the engine by means of the bar 9 and the T-shaped bearing post 10. An operating shaft 8 is horizontally mounted in said bearing post 10 and on the end portion of said shaft is secured the sprocket wheel 6 which is connected with the other sprocket wheel 5 by the chain belt 7. An oil cup 12 is provided for lubricating said shaft 8.

A distributor rotor 13 made of insulating material is secured on the end of said shaft 8 and is given substantially a square form with each corner cut off in circular form as at 14. A recess 15, extending from the axis of said rotor 13 to one of said circular corners 14, is cut in the outer face of said rotor 13, and a contact arm 16 is carried in said recess with a spring behind said arm to keep said arm yieldingly flush with the face of said disk at all times. A distributor case 18, made of insulating material, is loosely carried on the end portion of said shaft 8 and is kept from revolving with said shaft by means of the timer element E which is screwed into the periphery of said case in the threaded hole 19. The said distributor rotor is operated within said casing 18, and is held therein by the cap 20 also made of insulating material and held in place as a cover for said case by suitable set screws. Lead wires a, b, c, d and e are spaced apart and fastened in said cap 20 and the wires a, b, c, and d are connected with the respective spark plugs 1, 2, 3, and 4 while the wire e is connected with the secondary of said coil C. Contact screws a', b', c', d' and e' are the means I use to hold said wires in said cap 20 and the said arm 16 contacts with said wires when said cap is made to rotate, electrically con-

necting the said wire *e* with each of said wires, *a*, *b*, *c*, and *d* respectively, and thereby conveying the high tension current to the respective spark plug for the purpose of firing the respective cylinders. The timer element *E* consists of a nut 21 axially carrying therein the low tension contact post 22, and threaded to receive one end portion of the insulating tube 23 which is externally threaded and connects the said nut 21 and sleeve 24. A contact thimble 25 is carried within said tube 23 and a coil spring 26 is operated within said thimble 25. The said sleeve 24 is electrically grounded through the post 10 and has a radially extended pin 27 therein by means of which the spark may be advanced or retarded by slightly rotating said casing 18 on the shaft 8. A contact plunger 28 is operated within an axial opening 29 in said sleeve 24, which opening has a narrowed neck as shown at 30 forming a shoulder in said opening 29 and against which a spring 31 bears. A shoulder 32 is formed on the said contact plunger 28 and said spring 31 operates between said shoulders 30 and 32.

The operation of my device is as follows: I use an induction coil *C*, of any of the well known makes; and with electric energy developed by the battery *B* the device is grounded through the bearing post 10 by means of a wire *f* which connects said bearing post 10 and the said contact sleeve 24. When the engine *A* is operated the said shaft 8 is made to rotate through the sprocket wheels 5 and 6 and chain belt 7, and as said shaft 8 is rotated the distributor rotor 13 carrying the arm 16 is likewise rotated within the said case 18. The contact screws *a'*, *b'*, *c'* and *d'* are respectively brought in touch with the said arms 16 and as it is in touch at all times with the central and high tension wire *e* through the contact screw *e'*, the secondary or high tension current is carried, through the spark plugs and fires the respective cylinders whenever the arm 16 connects one of said contact screws *a'*, *b'*, *c'* or *d'* as controlled by the timer element *E*. The larger end of said plunger 28 extends without the sleeve 24 and bears against the irregular periphery of the rotor 13, and when the annular portions 14 of said rotor are in touch with said plunger 28 the secondary of the coil is established through the particular spark plug that is in electrical contact through the arm 16 and

its wire, and firing occurs in the cylinder within which the spark plug is secured. The order of firing is controlled by the placing of the lead wires *a*, *b*, *c*, and *d*. Should the operator desire to advance or retard the spark, for instance to retard it, to prevent back firing of the engine, he will move the pin, 27 by its connections with levers not shown, in the direction that the timing shaft *D* is rotated in order that the plunger 28 will not reach one of said flat faces on the rotor as quickly as when the members are in their normal position.

Having thus described my invention I desire to secure by Letters Patent and claim:—

1. The combination with a rotatable shaft, of a distributor rotor secured on the end of said shaft having portions of its periphery annular and other portions flat and with a radially disposed recess cut in its end face; a distributor arm carried in said recess; an insulating casing within which the said rotor is operated; a cap for said casing; conductor wires secured in said cap against which said arm is adapted to bear; and a timer element carried in the periphery of said casing consisting of a sleeve, a nut, an insulating tube connecting said sleeve and nut, a contact thimble carried in said nut, a contact plunger carried in said sleeve adapted to bear at one end on the peripheric face of said rotor and to be brought in contact with said thimble at the other end as said shaft is rotated.

2. The combination with an internal combustion engine having a rotary shaft, of an induction coil; a battery; a rotor secured on said shaft; an arm carried in the face of said rotor; a casing within which said rotor is operated; conductors in the end of said casing against which said arm is adapted to bear when contiguous; a sleeve secured in the periphery of said casing; a nut carrying a contact post; an insulating tube connecting said sleeve and said nut; a contact thimble carried in said nut; a plunger carried in said sleeve with one end portion bearing against said rotor and the other end adapted to bear against said thimble at intervals when said rotor is operated to form a high tension circuit including said coil and the spark plugs of said engine.

In testimony whereof I have affixed my signature.

ARTHUR DICKERSON.
